J. B. HADAWAY

ART OF ATTACHING RUBBER HEELS

Filed July 25, 1921

INVENTOR.
John B. Hadaway.

UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

ART OF ATTACHING RUBBER HEELS.

Application filed July 25, 1921. Serial No. 487,314.

This invention relates to the art of attaching heels and, particularly, rubber heels or composite heels having a rubber top section.

5 In the following specification and claims the term "rubber heel" is used in the sense in which it is commonly employed in the trade, and it should be clearly understood that in no case is it to be construed as 10 limited to a heel consisting only of pure rubber, but that such heels are to be included as have the common characteristics of so-called rubber heels and may be made of rubber, rubber compositions, or other 15 suitable compositions of an elastic, yielding, cushioning or resilient character.

Elastic, cushion heels sometimes consist wholly of such a composition as above described but it is, perhaps, at the present 20 time, more common to combine a rubber top section with a substantially rigid base section made of leather, leatherboard or other suitable material, heels of the type last referred to being commonly called composite

25 heels. Certain features of the invention are applicable to both composite heels and heels made entirely of rubber or like material, while other features of the invention are of especial utility in connection with composite 30 heels, all as will appear clearly hereinafter.

Rubber heels are usually provided with washers embedded in the body of the heel, the attaching nails being driven through the washers until the nail heads engage the 35 washers. The purpose of the washers is to prevent the nail heads from pulling through the yielding material of the heel and permitting the heel to become separated from the shoe. In the ordinary rubber heels of 40 commerce the tread surface of the heel is perforated by holes which are left by the washer supporting pins in the mold in which the heel is vulcanized in the process of its manufacture, and after the heel is attached to a shoe the heads of the attaching 45 nails are visible when they are seated on the washers near the bottoms of the perforations. This is not seriously objectionable in cheap work but in the higher grades of 50 shoes it is desirable that the heels be blind

nailed, so that the nail heads shall not be visible in the finished shoe.

One object of the invention, therefore, is to produce a shoe having a rubber heel attached by blind nailing, and to this end in 55 an important aspect, the invention resides in a method of attaching rubber heels, which comprises stretching the rubber, inserting an attaching fastening through the stretched rubber, and then permitting the rubber to 60 resume its original state, that is to say, to close over and conceal the head of the attaching fastening. By placing the rubber under tension in the area where the attaching nail is to be driven, mutilation of the 65 rubber by the attaching nail and the driver is minimized and when the tension is released the rubber closes together over the head of the nail so completely as to effectually conceal the latter and scarcely to 70 leave a visible mark. This feature of the invention is applicable to both whole rubber heels and composite heels, indeed to any heel having a rubber top section.

There are two known methods of attaching composite heels. According to one of 75 these methods the leather or leatherboard base section is first attached to the shoe in the same manner as any ordinary heel; then, in a separate operation, the rubber top section is attached by nails driven into the base section, and sometimes passing through and clinching in the insole. This method requires two separate and distinct heel attaching operations, which are usually performed on different machines, and involves 80 substantial expense. According to the second method of attaching, the rubber section is cemented to the base section preliminarily 85 and the composite heel thus produced is attached in a single nailing operation by nails passing through both sections in clinching in the insole. This second method, while effecting a substantial saving in labor cost, 90 has the drawback that when a shoe repairer undertakes to replace the worn rubber heel section by a new one he has to pull out all the attaching nails in order to remove the old rubber section, thus allowing the base 95 section of the heel also to separate from the 100

shoe. Another object of the invention, therefore, is to devise a novel method of attaching composite heels which shall have all the advantages of both of the former methods 5 without any of the drawbacks of either.

To this end, in another aspect the invention consists in a method of attaching composite heels which comprises pressing a heel upon a shoe, and driving a plurality of attaching fastenings to different depths at a single operation. The heads of part of the fastenings may be driven entirely through the rubber section until they are located substantially in the outer face of the base section, the remaining nails being driven less deeply so that their heads remain embedded in the rubber section and serve as securing means for the rubber section. The first mentioned set of nails serve as securing means 20 for the base section and when it becomes necessary to repair the shoe the rubber section can be removed without disturbing them or dislocating the base section with respect to the shoe. This procedure may advantageously be combined with the blind nailing previously described, the rubber heel having indications arranged upon its tread face at the points where the attaching nails are to be driven and washers embedded in the 25 heel in register only with such of the indications as define the locations of the second set of attaching nails above referred to, namely, those which serve as attaching means for the rubber section.

When attaching composite heels at a single nailing it has been customary heretofore to make the base section of the heel somewhat larger than the rubber section and to apply the attaching pressure, which is required in the 30 nailing operation, to that portion of the base section which projects beyond the edges of the rubber section. It has been considered impracticable to apply the attaching pressure through the rubber section because the latter is of a sufficiently yielding quality to be 35 seriously distorted by any very considerable pressure, making it impossible to drive the nails through the washers; and, indeed, it is practically impossible to transmit sufficient attaching pressure through a rubber section which is unconfined at its edges. Rubber, 40 however, when confined, is an almost incompressible substance and in another aspect of the invention a method of attaching is provided which consists in placing an assembled composite heel upon a shoe, confining the rubber section on all edges against expansion, and applying heavy pressure to the base section through the confined rubber section. 45 By thus completely confining the rubber section distortion thereof is prevented, it becomes possible to apply any desired amount of pressure to the base section, and a considerable saving in stock is effected since it

is not necessary to make the base section materially larger than the rubber section. 65

Further features of the invention relate to improved heeling machine construction by the aid of which my new and improved method may be conveniently practised, and include a nailing die having nozzles or projections arranged to enter the depressions in the tread face of an elastic heel, said nozzles or projections differing in shape or size from the depressions, whereby the material 70 around the depressions is stretched when pressure is applied; mechanism constructed and arranged to drive simultaneously two gangs of fastenings to different depths in a composite heel; and other features of improvement which will appear more completely from the following detailed description of a preferred form of the invention, read in connection with the accompanying drawings, in which— 75

Fig. 1 is a view partly in perspective and partly in section of a rubber heel made in accordance with the invention;

Fig. 2 is an exploded view showing the under side of the rubber heel section and the 90 top of a portion of a leather or leatherboard base section with which it is to be assembled to form a composite heel;

Fig. 3 is a view of a portion of a heeling machine embodying the invention, with the 95 work in position;

Fig. 4 is an enlarged detail of a portion of the nailing die of the heeling machine with a rubber heel section in position to begin the application of pressure; 100

Fig. 5 is a view similar to Fig. 4 showing the position of the parts after an attaching nail is driven;

Fig. 6 is a view similar to Fig. 5 showing the condition of the heel after the pressure 105 is released; and

Fig. 7 is a sectional view upon a plane indicated by the line 7—7 of Fig. 2.

Referring now to the drawings, 10 indicates a rubber heel section or lift and 12 indicates 110 a rigid base section which may be built up of lifts of leather, leatherboard or other suitable material.

The rubber section 10 is preferably of uniform thickness throughout and comprises 115 a central, flat portion and a curved, edge portion 14 extending around the periphery of the flat portion, with the exception of the breast edge. The heel thus constructed is, in effect, concave upon its inner, or contacting, face and convex upon its outer or tread face, but becomes flattened when it is pressed upon a shoe and by reason of the inwardly curved marginal portion 14 a tight joint around the edge is assured without the necessity of resorting to cement. On the inner face of the rubber lift are formed two frusto-pyramidal projections 16 which are 120

shown as square in cross section, and the tops of which lie approximately in the same plane as the edge 18 formed by the intersection of the inner face and the curved 5 periphery of the lift.

In the tread face of the lift are formed a plurality of shallow, approximately conical depressions 20 arranged in the pattern of the desired nailing. These depressions act 10 as indicating means to show where the nails are to be driven. Washers 22 are embedded in the rubber in register with certain of the indicating depressions 20, as will be explained in more detail hereinafter. Contrary to the usual practice, the bottoms of 15 the depressions 20 are completely closed, or imperforate, there being a substantial thickness of rubber between the bottom of the depression and the corresponding washer, as clearly shown at 24 in Fig. 1. The necessary 20 holes made by the washer supporting pins in the vulcanizing mold in which the heel is manufactured, which are usually to be found in the tread face of a rubber heel, are, in 25 this instance, in the inner face and by reference to Fig. 2 wherein these holes are indicated by the reference numeral 26, the 30 locations of the washers 22 in the heel section may be readily determined, it being understood that there is such a washer at the 35 bottom of each of the holes 26. By comparison of Figs. 1 and 2 it will be seen that certain of the depressions 20 have no corresponding washers, the rubber being unbroken beneath such depressions, as shown 40 at 27 in Fig. 1.

In the outer face of the base section 12 are two cylindrical recesses 28 corresponding to the projections 16 on the contiguous 45 face of the rubber section 10. The top of the pyramidal projection 16 is preferably smaller in every horizontal dimension than the diameter of the recess 28, as is also the shorter diameter of the base of the pyramid, 50 while the diagonal of the base of the pyramid is preferably greater than the diameter of the recess 28, with the result that the projection will enter the recess readily while contact of the projection with the walls of 55 the recess is insured and, consequently, accurate register of the two sections of the heel is secured. Furthermore, the material of the projections 16 being of a yielding nature, the accuracy of the registration is practically unaffected by shrinkage or expansion of the recesses 28, due to various 60 conditions of temper of the base section of the heel.

The sections 10 and 12 are preliminarily 65 attached together by two nails 30 driven through the two washer holes 26 nearest the projections 16 and clinched on the under side of the base section, as shown in Fig. 7. By utilizing the particular washers nearest 70 the projections 16 for these nails any danger

of the projections 16 being pulled out of the recesses 28 by the natural tendency of the rubber heel to spring away from the base is avoided. Such a contingency, of course, would involve danger of destroying the 75 proper register of the two sections.

Assuming the composite heel to have been assembled, as above described, it is ready 80 for attachment to a shoe. Fig. 3 shows the upper portion of a common commercial type 75 of heelng machine which, with appropriate modifications, is suitable for use in connection with my invention. According to the invention the nailing die is provided with a series of nozzles or projections 32 upon its 85 pressure applying face, said nozzles or projections being arranged to enter the depressions 20 in the tread face of the heel and the taper of the nozzles or projections being less than that of the depressions 20 or, in 90 other words, the extremities of the nozzles or projections being greater in diameter than the bottoms of the cavities, the nozzles or projections are forced into the rubber around each of the cavities and the rubber is 95 stretched or put under tension when pressure is applied.

It is a fact well known to those familiar 100 with the manufacture of rubber heels that even heels which are vulcanized in the same 95 mold are not all alike. Such heels vary more or less in respect to the relative locations of the washers therein and in respect to their sizes and shapes. This is due partly to lack of absolute uniformity in the batches 105 of rubber composition and partly to shrinkage of the heel after its removal from the mold. The shrinkage is not uniform either in direction or amount. A valuable feature of the present invention resides in the means 110 provided for positively locating all the elements of the heel with exactness in their proper relation to the shoe and maintaining them securely in such relation while the attaching nails are driven. As shown in Fig. 4, the axes of the driver passages 34, and of the nozzles or projections 32, are substantially vertical while the axes of the holes 26 and the cavities 20 are, before the application 115 of pressure to the heel, inclined. By forming the nozzles or projections 32, as shown and described, accurate location of the heel with respect to the driver passages 34 is insured and misplacement of the washer bearing portions of the heel under the 120 pressure of the heelng machine is prevented. The nozzles or projections 32 are located in a cavity in the face of the nailing die, surrounded by a rigid, strong wall or ring 36 which is of substantially the same depth as 125 the thickness of the rubber heel section 10 and which fits the periphery of the rubber section fairly closely. Thus, the wall or ring 36 accurately locates and confines the 130 edge of the heel while the nozzles or projec-

tions 32 locate the washer bearing portions of the heel, and the cavities 20, in predetermined positions, both with respect to the driver passages 34 and with respect to the 10 peripheral edge of the heel. By this means the heel, no matter how it may have become distorted, is forced into its proper shape and held unyieldingly with all its elements in their proper, predetermined positions while the attaching nails are being driven.

The composite heel having been inserted in the ring 36 a shoe is placed upon the jack 38 and positioned in the heelng machine beneath the heel. The shoe and heel are then 15 pressed together, the rubber section of the heel being flattened into contact with the base section, the washers being alined with the nozzles or projections 32, and the rubber section being held positively against expansion by the ring 36. The heavy pressure of the heel attaching machine is now applied and, the rubber section being confined against 20 lateral expansion, the pressure is transmitted through it, forcing the base into solid contact with the heel seat of the shoe. The rubber around the bottoms of the cavities or depressions 20 is now stretched or under tension and the drivers 40 are caused to descend to drive home a load of nails, which 25 has previously been inserted in the nailing die. Attaching nails, are, of course, omitted from the two holes in the nailing die which correspond to the previously inserted nails 30, and the nails which are driven by the heelng machine are of different lengths, the longer ones being shown at 42 and the shorter ones at 44. The drivers 40 are also of different lengths, the longer drivers being utilized to drive the shorter nails and vice 35 versa. As the nails are driven they cut their way through the stretched rubber, as shown in Fig. 5, and when the pressure is removed from the heel the rubber, in resuming its 40 normal condition, closes over the heads of the nails, as shown at 46, effectually and completely concealing them from view. The short nails 44 are driven into the cavities 20 for which there are no corresponding 45 washers and are driven completely through the rubber section until their heads are seated on the outer face of the base section, their points being clinched in the insole 48. The longer nails 42 are driven through the 50 washers 22 until their heads are seated in the washers and their points are also clinched in the insole, since the nails 44 serve only to secure the base 12 to the shoe while the nails 42 secure both the rubber 55 section and the base. When the shoe repairer removes the rubber section he will pull out only the nails 30 and 42, leaving the base of the heel still secured to the shoe by the nails 44.

60 65 The original shape and qualities of the

rubber section 10 are such that, with the attaching nails driven as described, the rubber heel is securely attached and hugs closely to the base, especially around the edge. While no cement is used between the rubber 70 section and the base section all the advantages of a cemented composite heel are secured and the expense of the cement and the labor required to apply it are eliminated. Furthermore, a blind nailed rubber heel of 75 pleasing appearance is secured which is suitable for the very best class of footwear, and may be removed in the process of repairing the shoe without destroying the integrity of the remainder of the heel portion 80 of the shoe. This result is attained in a single attaching operation at a minimum expense.

The novel composite heel and shoe construction herein illustrated and described is 85 claimed in a separate application Serial No. 604,761 filed Dec. 4, 1922, as a division of the present application.

Having described the invention, what is new and desired to be secured by Letters 90 Patent is:—

1. That method of attaching rubber heels which comprises stretching the rubber, inserting an attaching fastening through the stretched rubber, and then permitting the 95 rubber to resume its original state.

2. That method of attaching rubber heels which comprises placing the rubber in a localized area of the heel under tension, driving an attaching fastening through 100 said localized area of tensioned rubber, and then releasing the tension.

3. That method of attaching a rubber heel which comprises placing a plurality of localized areas of the heel under tension, 105 inserting attaching fastenings through the tensioned portions of the rubber, and then releasing the tension.

4. That method of attaching rubber heels which comprises placing a portion of the 110 heel under tension, driving an attaching nail through the tensioned rubber to a point where the head of the nail is within the body of the heel, and then releasing the tension and allowing the rubber to close over the 115 head of the nail.

5. That method of attaching a heel to a shoe which comprises assembling a heel top section with a heel base section, then pressing the assembled heel upon a shoe, and thereafter driving to different depths at a single operation a plurality of attaching fastenings, certain of said fastenings being effective to attach only the base section to the shoe and others of said fastenings being effective to attach the top section to the shoe. 120 125

6. That method of attaching a composite heel consisting of a rigid base section, and a rubber top section which comprises pressing the assembled heel upon a shoe, and there- 130

after driving a plurality of attaching nails, part of said nails being driven to such a depth that their head ends are substantially flush with the plane of contact between the 5 base and rubber sections and others of said nails being driven to a depth where their heads are within the body of the rubber section.

7. That method of attaching a composite 10 heel consisting of a rigid base section and a rubber top section which comprises placing the assembled heel upon a shoe, confining the rubber section on all edges against expansion, and applying heavy pressure to 15 the base section through the confined rubber section.

8. That method of attaching a composite 20 heel consisting of a rigid base section and a rubber top section which comprises placing the base section and the top section upon a shoe, confining the rubber section against expansion, whereby it becomes substantially 25 incompressible, applying heavy pressure to the base section through the incompressible rubber section, and driving attaching nails through both sections into the shoe.

9. Means for attaching rubber heels comprising heel engaging instrumentalities constructed and arranged to stretch the rubber 30 at a place where an attaching fastening is to be inserted, and means for inserting a fastening through the stretched rubber.

10. Mechanism for attaching a composite heel at a single nailing comprising means 35 for pressing the heel upon a shoe, and mechanism constructed and arranged to drive simultaneously two gangs of fastenings to such depths that the heads of the fastenings of one gang lie substantially in the plane of contact of the sections of the heel 40 and the heads of the fastenings of the other gang lie within one of said sections.

11. In a heel attaching machine for attaching heels having depressions in their 45 tread faces, a nailing die having projections arranged to enter and engage the walls of said depressions, said projections differing in shape from the depressions.

12. In a heel attaching machine for attaching heels having cup shaped depressions in their tread faces, a nailing die having 50 projections upon its pressure applying face arranged to enter said depressions, the extremities of said projections being greater in diameter than the bottoms of the cavities, 55 whereby the material around the cavity is stretched when pressure is applied.

13. In a heel attaching machine for attaching rubber heels having cup shaped depressions in their tread faces with the axes 60 of the depressions disposed at an inclination to the tread face of the heel, a nailing die having a flat, pressure applying face provided with projections arranged to enter 65 said depressions and position them in pre-

determined, relative locations, the extremities of said projections being greater in diameter than the bottoms of the cavities, whereby the rubber around the cavities is stretched, and the axes of said projections 70 being substantially normal to said flat face of the nailing die.

14. In a heel attaching machine for attaching heels having depressions in their tread faces, a nailing die having projections 75 arranged to enter and engage the walls of said depressions, said projections differing in size from the depressions.

15. In a heel attaching machine for attaching heels having depressions in their tread faces, a nailing die having projections 80 arranged to enter and engage the walls of said depressions, said projections differing in shape and size from the depressions.

16. In a heel attaching machine for attaching heels having depressions in their tread faces, a nailing die having projections arranged to enter and fill said depressions, and a surrounding rigid wall fitting and confining the entire intended periphery of the 90 attached heel.

17. Means for attaching elastic heels having depressions in their tread faces comprising heel engaging instrumentalities constructed and arranged to force the depressions into predetermined, relative positions 95 and simultaneously to confine the entire edge of the heel against expansion.

18. In a machine for attaching heels having depressions in their tread faces and having a normal shape different from that which it is intended they shall have when attached to shoes, attaching instrumentalities comprising means for bending the heels to said intended shape, means for positively 100 locating the depressions in predetermined relative positions, and means for driving attaching nails.

19. In a machine for attaching heels having depressions in their tread faces and having a normal shape different from that which it is intended they shall have when attached to shoes, attaching instrumentalities comprising means for forcing the heels to said intended shape, and means for locating the periphery of a heel and the depressions separately in predetermined, relative 110 positions.

20. In a machine for attaching heels having depressions in their tread faces and having a normal shape different from that which it is intended they shall have when attached to shoes, attaching instrumentalities comprising means for forcing the heels into said intended shape, and means for locating and positively maintaining the periphery of the heel and the depressions separately in predetermined, relative 120 positions.

21. The method of attaching composite 125 rubber and leather heels to shoes, consisting

in combining and assembling a rubber top lift and a leather or composition base in their proper position relative to each other by attaching means driven through one of

5 the named elements and into the other, and thereafter firmly securing both elements to the shoe.

22. The method of attaching composite rubber and leather heels to shoes, without 10 the use of cement, consisting in securing the rubber heel to the leather base by nails, and thereafter nailing both the rubber heel and the leather base simultaneously to the shoe, and clinching the nails inside the shoe.

15 23. The method of attaching composite rubber and leather heels to shoes, consisting in combining and assembling a rubber top lift and a leather or composition base in their proper position relative to each other 20 by attaching means driven from the tread face of the rubber top lift through and into the base, and thereafter firmly securing both elements to the shoe.

24. The method of attaching composite rubber and leather heels to shoes, without 25 the use of cement, consisting in securing the rubber heel to the leather base by nails driven from the tread face of the rubber

heel into the base, and thereafter nailing both the rubber heel and the leather base 30 simultaneously to the shoe, and clinching the nails inside the shoe.

25. Means for attaching an elastic heel comprising a heel engaging, fastening guiding nozzle, a work support, said nozzle and 35 work support being relatively movable toward each other, means for effecting relative approaching movement of the nozzle and work support to cause the nozzle to tension the material of a heel upon the work 40 support, and a driver for inserting a fastening through the nozzle into the tensioned material.

26. A machine for attaching rubber heels having in combination a tapered nozzle, a 45 work support, means for causing relative movement of the work support and the nozzle to force the nozzle into the rubber of the heel, thereby displacing and tensioning the rubber adjacent to the nozzle, and a driver 50 operative to drive a fastening through the nozzle into the tensioned rubber.

In testimony whereof I have signed my name to this specification.

JOHN B. HADAWAY.
